FIG. 5.

UNITED STATES PATENT OFFICE.

EARL H. PLAISTED AND ARTHUR O. BLACK, OF BUTLER, PENNSYLVANIA.

AUTOMATIC TIMING DEVICE FOR CLOSED CIRCUITS.

1,267,690.

Specification of Letters Patent.

Patented May 28, 1918.

Application filed February 20, 1917. Serial No. 149,815.

To all whom it may concern:

Be it known that we, EARL H. PLAISTED and ARTHUR O. BLACK, residents of Butler, in the county of Butler and State of Pennsylvania, have invented a certain new and useful Improvement in Automatic Timing Devices for Closed Circuits, of which the following is a specification.

The present invention relates to electrical devices, and more particularly to a device for automatically timing a closed circuit, such as used in telephony.

An object of the present invention is to provide an improved device for indicating, in minutes and fractions thereof, the time during which a telephone call circuit is closed, and for actuating a final signal at the expiration of a desired period of time for which the device may be adjusted.

20 A further purpose of the present invention is to provide a device of this character which may be included in telephone circuits already in use, and which is relatively simple in construction and comprising but relatively few parts.

25 The invention is primarily intended to indicate to a telephone operator, the exact time during which any circuit is closed to thus provide a positive means for determining the time, which at present is left to the judgment of the operator who handles the calls.

30 The above, and various other objects and advantages of this invention will be in part described, and in part understood, from the following detailed description of the present preferred embodiment of the invention, the same being illustrated in the accompanying drawings wherein:

40 Figure 1 is a side elevation of a timing device constructed according to the present invention, parts being broken away, and parts indicated in dotted line.

Fig. 2 is an end elevation of the same.

45 Fig. 3 is a fragmentary end view of the device, showing a section through one side thereof.

Fig. 4 is a similar view showing a section through the opposite side of the device.

50 Fig. 5 is a diagrammatic view of the device of this invention and the circuits connected thereto.

Referring to these drawings, wherein like parts are designated by similar characters 55 of reference throughout the several views, 10 designates a base of any suitable form,

provided at one end, which may be termed the inner end, with an upright 11 from which forwardly projects a magnet 12. The magnet 12 is provided with a core 13 provided upon its outer end with a relatively flat depending pole-piece 14 overhanging the base 10.

The upright 11 pivotally supports the inner end of an armature 15 which extends outwardly and terminates substantially beneath the pole-piece 14. The upright 11 is also provided with a bracket arm 16 which extends outwardly over the magnet 12 and terminates substantially above the pole-piece 14. The arm 16 is provided with laterally extending studs or projections 17 adapted to support a second armature 18.

The second armature 18 is of bell-crank formation and has one arm thereof projecting downwardly into closely spaced relation from the pole-piece 14. The opposite arm of the armature 18 is normally held against the upper side of the bracket arm 16 by means of a leaf spring 19 secured at one end to the bracket arm 16 and bearing at its free end against the adjacent free extremity of the armature 18. The spring 19 normally urges the armature 18 from the pole-piece 14, and the lower armature 15, by its weight, is normally urged toward the base 10. An adjustable rest 20, in the form of an elongated screw, projects outwardly from the upright 11, and bears against the lower side of the armature 15 to support the same at the desired distance from the lower end of the pole-piece 14. Preferably, the lower end of the pole-piece 14 is provided with a covering 21 of brass or the like to insure the quick release of the armature 15 when the pole-piece 14 is deenergized.

The magnet 12 is provided with three windings; a light winding 22 adapted to produce a relatively weak magnetic flux at the pole-piece 14 to attract the armature 18, a larger winding 23 adapted to augment the winding 22 and increase the magnetic flux of the magnet, and a third winding 24 which may be wound in an opposite direction from the winding 23, and which is of the same capacity as the magnet 23 to neutralize or deenergize the same.

Preferably mounted upon the base 10 at the outer end of the magnet 12 is a vertical support or bracket 25 carrying a transversely extending spindle 26. A ratchet wheel 27 is mounted on the spindle 26 and is adapted

- to be intermittently advanced in one direction of rotation by means of a pawl 28. The pawl 28 may be in the form of a relatively flat spring metal strip secured at one end 5 to the armature 15, adjacent to the pivoted end of the latter, and being sprung slightly upward from the armature at the outer end thereof, and being turned upwardly for engagement with the teeth of the ratchet wheel 27. The armature 15 and the pawl 28 are so 10 adjusted that upon each actuation of the armature the wheel 27 is advanced one tooth.
- The armature 18 is provided with an outwardly extending spring arm 29 which overhangs the wheel 27, and is provided upon its free upturned end with a depending spring dog 30 for engagement with the teeth of the ratchet wheel 27 to hold the latter from 15 retrograde movement. A drum 31 is connected to the ratchet wheel 27 to turn therewith, and is provided upon its peripheral surface with circumferentially extending rows of graduations indicating fractions of 20 a minute. The ratchet wheel 27 and the drum 31 are normally urged to turn in one direction by a spring 32, the latter having one end secured to the drum, and its opposite end secured to the support 25. The 25 drum 31 is provided upon one side with a radially projecting lug 33 adapted to engage a stop pin 34 carried by the support 25 for normally holding the drum and the ratchet wheel in a predetermined position of rest.
- The support 25 carries a contact pin 35 30 which is located adjacent to the stop pin 34, and which is adapted for engagement with the lug 33 when the drum and the ratchet wheel substantially complete a full turn.
- As shown in Fig. 2, the drum 31 is preferably mounted upon one side of the ratchet wheel 27, and the latter is provided upon its opposite side with an outwardly extending contact finger 36 adapted to wipe across a 40 plurality of closely spaced-apart circuit closing segments 37, 38, 39 and 40. These circuit-closing segments are secured to the support 25 and have interposed between them and the support an insulation 41, of 45 mica or the like. The circuit closing segments are provided in their adjacent ends with socket openings 42 into which may be fitted plugs 43 for connecting any two or more of the segments together.
- Referring now to Fig. 5, 44 designates a 50 circuit which may be associated with a subscriber's telephone line, trunk or connecting circuit, adapted to be closed by a switch 45 in the form of a jack-plug, a key or the like.
- The wire 44 is connected through binding 55 post 46 and branch wires 47 and 48 with the windings 22 and 23, respectively. The opposite end of the winding 22 is connected by wire 49 and binding post 50 to battery or 60 exciter 51 and is then grounded.

The opposite end of winding 23 is connected by wire 52 to a circuit closer 53, the connection being made through binding post 54.

The circuit closer 53 is actuated by a plurality of tappets 55 which are spaced apart at predetermined points upon a time wheel 56, the latter being of any suitable construction and being connected to the ordinary master clock. The wheel 56 is preferably of that type adapted to complete a revolution every minute, and the tappets 55 are preferably arranged at ninety degrees apart to engage the circuit closer 53 at intervals of fifteen seconds. The opposite side 80 of the circuit closer 53 is connected to a battery or exciter 57 which is grounded.

One end of the winding 24 of the magnet is connected to the wire 52, and the opposite end thereof is connected by wire 58 to the 85 fixed contact pin 35, in the path of the intermittently rotatable member.

The segment 40 is connected by binding post 59 to wire 60 which leads to an exciter 61 which is grounded through wire 62, the 90 wire 62 including a lamp 63, or the like.

The operation of the device is as follows:

When the apparatus associated with subscriber's line, trunk or connecting circuits is closed, by means of the device 45, the circuit 95 closed is through wire 44, branch 47, winding 22, wire 49, exciter 51, and to ground. The current passing through this circuit energizes the magnet 12 sufficiently to actuate the armature 18 and move the dog 30 into 100 engagement with the teeth of the ratchet wheel 27. The continuously rotating minute wheel 56 brings one of the tappets 55 into engagement with the circuit closer 53 to close the same and complete the following 105 circuit: wire 44, branch 48, winding 23, wire 52, circuit closer 53, exciter 57, and to ground. The magnet 12 is thus reinforced as the circuit is closed through both of the windings 22 and 23, and the magnetic influence of the pole-piece 14 is of sufficient flux 110 strength to not only hold the armature 18 against the pole-piece, but to also lift the lower armature 15, move the pawl 28 into engagement with the ratchet wheel 27 and 115 advance the latter one step.

The tappet 55 is carried past the circuit closer 53, and the circuit through the same is thus broken. The ratchet wheel 27 is turned against the tension of the spring 32, 120 and the dog 30, which is at all times held in engagement with the ratchet wheel 27 when the circuit is closed through wire 44, holds the ratchet wheel and the drum 31 from turning backwardly. Thus, as the tappets 125 55 are successively brought into engagement with the circuit closer 53, the ratchet wheel and the drum are intermittently advanced in the same direction and against the tension of the spring 32.

The circuit closing segments 37, 38, 39, and 40 are arranged in a circular row, and the segment 37 is spaced from the stop pin 34 a sufficient distance to affect the lapse of three minutes of time before the contact finger 36 engages the first segment 37. If all of the plugs 43 are in place, the lamp circuit will be closed through the four segments, the binding post 59, the wire 60, the 10 exciter 61, the wire 62, and through the lamp 63 to ground. Thus, at the end of three minutes the lamp 63 will be energized to give a visual indication of the lapse of the time.

15 The segments 37, 38 and 39 are of such length that it requires a lapse of two minutes of time for the contact arm 36 to wipe across each of the same. By successively removing the plugs 43 the time interval between the closing of the call circuit through the wire 44 and the closing of the lamp circuit may be increased.

Should the circuit through wire 44 be held closed for a sufficient length of time 25 to impart to the ratchet wheel 27 one complete turn, or substantially a turn, the radial projection 33 is brought into engagement with the contact stud 35 to connect the drum 31, which is grounded as shown in Fig. 5, 30 with one end of the reversely wound coil 24. When the minute wheel 56 actuates the circuit closer 53, the circuit is equally divided through the coils 23 and 24, the latter coil neutralizing or deenergizing the action of 35 the coil 23. Thus, the lower armature 15 cannot be raised when the circuit closer 53 is closed, and the dog 30 is held at all times in engagement with the teeth of the ratchet wheel 27 to prevent the same from returning 40 to normal position, and consequently prevent the immediate continuance of the intermittently actuated mechanism.

As soon, however, as the switch or device 45 is opened, the coil 22 is deenergized and the magnet releases the armature 18. The spring 19 now returns the dog 30 to its normal inactive position above the ratchet wheel 27, and the spring 32 is now free to rotate the drum 31 and the ratchet wheel 27 back 50 to its normal position of rest.

It is, of course, understood that the segments 37, 38, 39 and 40 may be in any desired number, and of any desired length to adapt the device to the various desired conditions of use. Various other modifications may be made in the details of construction and arrangement of circuits of the above-specified 55 described embodiment of this invention without departing from the spirit thereof, and being restricted only by the scope of the following claims.

We claim:

1. The combination with a main circuit adapted to be closed, a yielding time indicator normally held at a predetermined po-

sition of rest, means in said main circuit actuated when the latter is closed to prevent the retrograde movement of the time indicator, a time circuit adapted to be closed subsequent to the closing of the main circuit, 70 and means in the circuit for advancing the indicator when the main circuit is closed, both of said means being adapted to release the time indicator when said main circuit is opened, whereby the indicator is adapted to 75 automatically return to normal position of rest.

2. The combination with a main circuit adapted to be closed, of a time indicator 80 yieldingly held in a predetermined position of rest, retaining means included in the main circuit adapted to engage the indicator and prevent the retrograde movement thereof when the main circuit is closed, a time circuit adapted to be closed, advancing means 85 in said time circuit for actuating the indicator when the main circuit is closed, and a neutralizing circuit including the time indicator and said time circuit and adapted to retain the advancing means from operation when said indicator has moved through a predetermined distance, said retaining means being adapted to release the indicator when said main circuit is opened and said indicator being adapted to return to its normal position of rest when released. 95

3. The combination with a main circuit adapted to be closed, of a magnet provided with three windings, one of which is included in said main circuit, a time circuit 100 including a second winding and adapted to be closed at times to increase the potential of the magnet, the third winding of said magnet being a reverse winding, and a neutralizing circuit including the reverse winding and adapted to be closed for neutralizing the magnetic influence of the second winding. 105

4. In combination with a main circuit adapted to be closed, a magnet provided with 110 a single core and a pole-piece at one end, a retaining armature arranged adjacent to said pole-piece, an advancing armature arranged adjacent to said pole-piece, a time indicator arranged between said retaining 115 and advancing armatures and adapted to be controlled thereby, said magnet having a winding included in said main circuit for actuating the retaining armature upon the closing of the main circuit, the magnet also 120 having a second winding, a time circuit including the second winding and adapted to be closed at times to augment the first winding and attract the advancing armature when said main circuit is closed, said magnet 125 being further provided with a third reversely wound winding, and a neutralizing circuit including said third winding and the time indicator and adapted to be closed by the latter at a predetermined time for neu- 130

tralizing the magnetic action of said second winding of the magnet.

5. The combination with a main circuit adapted to be closed, of an intermittently actuated device, electric means in said circuit adapted to retain said device from retrograde movement when the circuit is closed, a time circuit connected to said means and adapted to be closed therethrough at predetermined times to augment the operating capacity thereof and advance said device, a de-energizing circuit connected to said means and to said device and adapted to be closed upon a predetermined advancement of the latter to deenergize said means and release the device, and means for returning the device to normal position when said main circuit is open.

6. The combination with a main circuit adapted to be closed, of a magnet including a grounded winding connected in said main circuit for energizing the magnet, a time indicator, a retaining armature arranged adjacent to the magnet for operation thereby to retain the indicator from retrograde movement upon the closing of said main circuit, a second armature arranged adjacent to the magnet for engagement with said indicator to advance the same, said magnet being provided with a second winding, a time branch circuit including said second winding and adapted to be closed therethrough and through the main circuit at predetermined times for increasing the magnetic influence of the magnet to attract said second armature and advance the indicator, said magnet being provided with a third reversely wound winding, and a deenergizing circuit including said third winding and said indicator, and adapted to be closed by the latter at predetermined times for neutralizing the magnetic influence of said second winding.

7. The combination with a main circuit adapted to be closed, a magnet having a winding included in said main circuit and being grounded, a time indicator, operable means adapted to be actuated by the magnet to retain the indicator from retrograde movement, a second winding on said magnet, a time circuit adapted to be closed at predetermined time intervals through said second winding to increase the magnetic influence of the magnet, advancing means associated with the magnet to be actuated thereby under the magnetic influence of both of said windings to advance the time indicator, and means for arresting the operation of the time indicator when advanced to a predetermined extent.

8. The combination with a main circuit adapted to be closed, a magnet having two coils one of which being included in said main circuit, to energize the magnet upon the closing of said main circuit, a rotary time

indicator including a ratchet wheel, an armature associated with said magnet and provided with a retaining dog adapted for interlocking engagement with the teeth of said ratchet wheel when said magnet is energized, a second armature, an advancing pawl carried by the second armature for engagement with said ratchet wheel, a time circuit adapted to be closed at predetermined time intervals through the other coil to augment the magnetic influence of the magnet and actuate said second armature to advance the time indicator, a third reversely wound coil carried by the magnet indicator, a third circuit including the third coil and the indicator and adapted to be closed therethrough when the latter is advanced a predetermined distance, said third coil when energized being adapted to neutralize the magnetic action of said second coil and arrest the operation of the said second armature, and means for returning the time indicator to its normal position of rest when said main circuit is open.

9. The combination with a main circuit adapted to be closed, an actuating device included in said main circuit, a time indicator associated with said actuating device to be moved thereby, a spring connected to said indicator for normally urging the same into a predetermined position of rest, and a deenergizing circuit including the indicator and said actuating device to arrest the operation of the latter upon the advancement of the indicator at predetermined distances, said spring being adapted to return the indicator to normal position when said main circuit is open.

10. The combination of a main circuit adapted to be closed, an actuating device included in said main circuit, a time indicator associated with said actuating device and adapted to be advanced thereby, a projection on said indicator, a stop adapted to engage the projection, a spring for normally holding the indicator in position to engage the stop against the projection, a contact pin arranged in the path of said projection, and a neutralizing circuit including said contact pin and indicator and said actuating device to arrest the motion of the latter when said projection engages the contact pin.

11. The combination with a main circuit adapted to be closed, of an actuating device included in said main circuit, a time indicator associated with said actuating device, said indicator being provided with a contact arm movable therewith, a row of contacts arranged in the path of said contact arm, a signal circuit including the last contact of the row, and means for connecting two or more contacts of the row to include the same in said signal circuit and vary the time of closing the same during the operation of the indicator.

12. The combination with a main circuit adapted to be closed, of actuating means included in said main circuit, an indicator associated with said actuating means, said indicator being provided with a movable contact arm, a row of spaced-apart contacts in the path of said arm adapted to be consecutively engaged thereby, a lamp circuit connected to the contact at the end of the row, and plugs detachably fitting between the contacts to electrically connect the desired number of the same in the row and vary the period of time from the operation of the indicator to the closing of the said lamp circuit. 10
